UNITED STATES PATENT OFFICE.

WILLIAM W. CAMERON, OF LA CROSSE, WISCONSIN, ASSIGNOR TO LA CROSSE PLOW CO., OF LA CROSSE, WISCONSIN, A CORPORATION OF WISCONSIN

TRACTOR-PLOW.

1,287,874.

Specification of Letters Patent. Patented Dec. 17, 1918.

Original application filed April 25, 1914, Serial No. 834,312. Divided and this application filed August 18, 1917. Serial No. 186,844.

To all whom it may concern:

Be it known that I, WILLIAM W. CAMERON, a citizen of the United States, and a resident of La Crosse, in the county of La Crosse and State of Wisconsin, have invented certain new and useful Improvements in Tractor-Plows, of which the following is a full, clear, and exact description.

10 The invention relates to tractor plows and is a division of the subject-matter set forth in an application filed by me April 25, 1914, Serial No. 834,312.

15 The object of the invention is to provide improved means for manually lifting a plow-carrying structure in a plow in which a power-operated crank-axle is ordinarily used to raise the plow.

20 This object is attained by employing a socket which is fixed to the power-operated axle and is operable by an ordinary rod or bar that is adapted to be removably inserted therein. A further object of the invention is to provide an improved lifting mechanism of this type in which the means for manually lifting the plow-carrying structure is disposed at the outer side of the landwheel where it can be easily manipulated.

25 30 The invention consists in the several novel features hereinafter set forth and more particularly defined by claims at the conclusion hereof.

In the drawings: Figure 1 is a front elevation of a plow embodying the invention. Fig. 2 is a longitudinal section, showing the mechanism for operating the crank-axle to lift the plow-carrying structure. Fig. 3 is a section taken on line 3—3 of Fig. 2. Fig.

40 4 is a detail plan of the socket and removable lever for manually operating the axle.

The plow comprises a land-wheel 20 at one side, a furrow wheel 21 at the other side, a crank-axle 24, having its end 23 mounted in the hub of the land-wheel 20, a stub-axle 25 mounted in the furrow-wheel 21 and adjustably secured in a bracket 26 in which is rigidly secured a standard 27. A bracket 28 is mounted on the end-portion 23 of the axle and a standard 29 is rigidly secured in said bracket. The opposite end 23 of the crank-axle is co-axial with the axle-portion 23. is journaled in a collar 30 which is vertically adjustable and slidable

on standard 27, and is supported upon bracket 26 by an adjustable eccentric 30. The land-wheel 20, crank-axle 24, stub-axle 25, furrow-wheel 21 and standards 27, 29, serve as a supporting structure for the front of the machine. The plowshares in desired number are secured to beams, the front ends of which are cross-connected by a front rail or angle bar 34, as more fully illustrated in the aforesaid application No. 834,312.

At each side of the plow-carrying structure, a bracket 37 is secured and each bracket is provided with a sleeve or guide 38 through which pass the standards 27, 29, which are sustained by the crank-axle. These sleeves and standards constitute a sliding connection between the wheel-supported front structure and the plow-carrying structure which permits the latter to be raised or lowered by the crank-axle and whereby both of the structures will be connected so as to be drawn together by the pulling force, and so that the crank-axle may be utilized to raise and lower the carrying structure. Power from the tractor will be applied to the bar 34 by a suitable draft connection. Any suitable means, such as a furrow-wheel or shoe, as well understood in the art, may be used to sustain the rear of the plow-supporting structure.

Crank-axle 24 is connected to raise and lower the front end of the plow-carrying structure by means of a pair of links 51, the lower ends of which are provided with boxings 52 whereby they are pivotally connected to the crank-axle. A block 55 is slidable on and adjustably connected to each link 51 by means of a screw 56 which is mounted in an offset lug 57 of the link. Each screw 56 is provided at its upper end with a crank by which it may be turned to raise or lower the block 55 and is held against vertical movement relatively to the link by a shoulder 60 above the lug 57 and a pin 61 below the lug. Brackets 62 are rigidly secured to the front rail 34 and a shaft 63 is journaled in said brackets. Cranks 64 at the outer end of shaft 63 respectively, are pivoted to the blocks 55. A hand lever 67 rigidly secured to shaft 63 and provided with a lock 68 is adapted to rock the shaft 63 to raise or lower the carrying structure relatively to the front supporting-structure. The lock 68 is adapted

to engage the teeth of a rack 69 which is fixed on bar 34.

A ratchet wheel 80 is formed on the hub of the land wheel 20 to operate the power-lift. The crank-axle is movable through successive half-revolutions in the same direction to alternately raise and lower the plow-carrying structure. The power-lift comprises a pair of dogs 81, pivoted, as at 82, 10 at diametrically opposite points, to one side of a two-armed lever 83 which is secured to the axle by a suitable key so as to rotate the axle and so as to hold the axle against rotation when the lever is locked. Each dog 15 81 is normally held disengaged from the ratchet 80 by a spring 85 between the dog and the lever 83. Stops 86 on the lever 83 limit the outward movement of the dogs by springs 85. Each dog is provided with 20 an inwardly extending stud 87 which is adapted to enter a segmental groove 88 formed in an extension of bracket 28 to successively hold the dogs in engagement with the ratchet until a full half revolution 25 has been imparted to lever 83 and the crank-axle. Lever 83 is normally locked against rotation to lock the crank-axle, by a locking bolt 89 which is normally and yieldingly held in operative position and in one of the 30 holes 97 on lever 83 which is secured to the axle. Bolt 89 is U-shaped and comprises a member 92 which is also guided in extension 91 and slideable therein. A controlling lever 94 for shifting the dogs 81 into engagement 35 with the ratchet wheel and for preliminarily releasing the lock 89 is pivoted to extension 91 by a bolt 95 and is provided with a cam 96 which is adapted to engage arm 92 of bolt 89 to withdraw the bolt from holes 97 40 in lever 83. Lever 94 is also provided with a stud 98 which is normally out of the path of dogs 81 and adapted to shift the uppermost dog into engagement with ratchet 80 against the force of spring 85, after lock 45 89 has been released from lever 83. An arm 99 is secured to lever 94 and a rod or cable 100 is connected to the upper end of said arm and extends to a convenient position on the tractor. Inclined surfaces which are 50 shown in my aforesaid application Serial No. 834,312 are formed on the lever 83 to force the locking dogs inwardly and into position to enter the holes 97.

The operation of the power-lift mechanism will be as follows: Assuming the plows to be lowered, the crank-axle will be in position shown in Fig. 1. To raise the plows, the operator will pull cable 100 which will cause lever 94 to rotate cam 96 and withdraw bolt 89 from hole 97 in lever 83. This will release the power-lift and after arm 94 has released the lock, stud 98 will force the upper dog 81 into engagement with ratchet 80. The rotation of the land wheel 20 will rotate ratchet 80 and the dog to-

gether and said stud 87 on the dog will pass into groove 88 to hold the dog in engagement with the ratchet until the crank has been shifted a half-revolution. Then lock-bolt 89 will pass into hole 97 upon the opposite end of lever 83 and automatically lock the crank-shaft in position to hold the crank-axle raised. This operation of the crank-shaft will cause links 51 to raise the front of the plow-carrying structure. When the plows are raised, a pull upon cable 100 will render the power-lift operative to impart a half-revolution to the crank-shaft 24 to lower the front end of the plow-carrying structure.

In tractor-plowing, it sometimes becomes necessary to raise or lower the plow-carrying structure when the plow is not being pulled forwardly, and the primary object of the present invention is to provide a simple device whereby this may be effected from a convenient point. For this purpose, portion 23 of the crank-axle is extended beyond the hub of the land wheel and a collar 104 is rigidly secured to the axle outside of the land-wheel. This collar is provided with a socket 105 which extends through the collar and is adapted to receive from either end a removable lever or bar 106 which may be conveniently carried on the tractor when not in use. To operate the crank-axle manually, it is only necessary to release the locking pin 89 so that the lever 83 will be free to rotate and then the bar 106 can be rotated to swing the crank-axle 24 from one of its alternative positions to the other. The socket 105 extends horizontally, so that the bar 106 will be free to move through the upper segment of a circle and through a half revolution.

The invention exemplifies an improved plow in which a crank-axle which is connected to operate the plow-carrying structure, is provided with a socket for a removable lever which can be operated from the land-side of the plow to shift it from one of its alternative positions to the other when the plow is stationary or any time that the power-lift should become inoperative.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a plow, the combination of carrying wheels, a plow carrying structure, a crank shaft sustained by the carrying wheels, mechanism operable by one of the carrying wheels for rotating the crank shaft to shift the plow-carrying structure, a device secured on said shaft and adapted to receive a readily detachable lever whereby the crank

shaft may be operated manually to shift the plow-carrying structure, and means for locking the crank shaft to hold the plow carrying structure.

5 2. In a plow, the combination of carrying wheels, a plow carrying structure, a crank shaft sustained by the carrying wheels, mechanism operable by one of the carrying wheels for rotating the crank shaft to shift the plow-carrying structure, a socket secured to the crank shaft and adapted to receive a readily detachable lever whereby the crank shaft may be operated manually to shift the plow-carrying structure, and 10 means for locking the crank shaft to hold the plow-carrying structure.

15 3. In a plow, the combination of carrying wheels, a plow carrying structure, a crank shaft sustained by the carrying wheels, mechanism operable by one of the carrying wheels for rotating the crank shaft to shift the plow-carrying structure, a device secured on said shaft and adapted to receive

a readily detachable lever whereby the crank shaft may be operated manually to shift the plow-carrying structure, and means for locking the crank-shaft to hold the plow carrying structure, said device being disposed adjacent the carrying wheel at the landside of the plow. 25

4. In a plow, the combination of carrying wheels, a plow carrying structure, a crank shaft sustained by the carrying wheels, mechanism operable by one of the carrying wheels for rotating the crank shaft to shift the plow-carrying structure, a socket secured to the crank shaft and adapted to receive a readily detachable lever whereby the crank shaft may be operated manually to shift the plow-carrying structure, and 30 means for locking the crank-shaft to hold the plow-carrying structure, said socket being disposed adjacent the wheel at the landside of the plow. 35

WILLIAM W. CAMERON.
